TENT FRAME

Filed Aug. 28, 1928

FIG. 1.

FIG. 3.

UNITED STATES PATENT OFFICE

DAN STROMBECK, OF NORDLAND, WASHINGTON

TENT FRAME

Application filed August 28, 1928. Serial No. 302,597.

This invention relates to tent supporting means and pertains particularly to a collapsible frame designed primarily for use in connection with tents of pyramidal formation.

5 The primary object of this invention is to provide a supporting structure which will maintain the tent canvas in the proper position, eliminating the usual center pole which is usually in the way and which it is desir-
able to remove from the tent structure.

The invention broadly contemplates the provision of a plurality of poles which are designed to be arranged in substantially vertical position against the inner face of the 15 tent wall, each pole carrying at its upper end an arm, which arms are attached to a center block member, which in turn supports an upright shaft designed to engage the central portion of the tent structure at the top or peak. The arms are hingedly attached to 20 their respective poles and are also attached to the central block member, thus permitting the frame to be folded for convenient storage or transportation.

25 A further object of the invention is to provide a tent frame of strong and durable construction and of a character which will enable one to readily raise the same to position.

The invention will be best understood from 30 a consideration of the following detailed description taken in connection with the accompanying drawing forming part of the specification and with the understanding, however, that the invention is not confined to any 35 strict conformity with the showing of the drawing, but may be changed or modified so long as such changes and modifications mark no material departure from the salient features of the invention as expressed in the 40 appended claims.

In the drawing—

Figure 1 is a view in side elevation of the tent frame, with one pole removed,

45 Fig. 2 is a top plan view of a portion of the frame,

Fig. 3 is a view of the upper part of the frame partly folded.

Referring to the drawing in detail, where-
in like numerals of reference indicate corre-
sponding parts throughout the several views,

the numeral 1 indicates the frame poles, each of which is pointed at its lower end as indicated at 2 and each of the poles carries adjacent the lower end and upon the outer side thereof a downturned hook member 3 to 55 which a suitable eyelet of the tent canvas may be attached to hold the canvas in taut condition over the frame. Each of the poles also carries at its lower end a step 4 which is provided to facilitate the erection of the frame 60 by the operator placing his foot thereon and forcing downwardly to cause the pointed forward end of the pole to penetrate the ground. The pointed ends 2 of the poles are iron capped to further facilitate their extension 65 into the ground and to protect the pole body during the insertion of the same.

At the upper end each of the poles has hingedly attached thereto as at 5, an arm member 6. These arms are designed to be 70 raised to a position substantially at right angles to their respective poles and so held by a hinged brace member 7 which spans the corner thus formed between the arm and pole. The arms have the faces of their outer 75 ends obliquely angled to conform to the complementarily angled abutting ends of the adjacent pole.

Each of the arms 6 is hingedly attached as 80 at 8 to a central block member 9 which, when the frame is set up, assumes a position upon the longitudinal center thereof. In the present instance, four poles are shown, in which case the arms 6 are connected to each of four 85 equi-distantly spaced points about the block 9. It is, of course to be understood that a greater or lesser number of arms and poles may be employed without departing from the 90 spirit of the invention.

The block member has a threaded aperture formed through the central portion thereof in which the threaded end of an upright stub pole 10 is designed to engage, the upper end of this pole being provided with a 95 pin member 11 for extension through the usual central eyelet formed in the peak of tents of the character in connection with which the present frame is designed to be used. This stub pole provides a convenient 100

means for tightening up the tent body when such procedure is necessary.

From the foregoing description, it will be readily seen that the present tent frame is designed to be quickly set up and when in set up position will support a tent canvas better than the usual center pole, without the disadvantage of having a pole or other structure in the center of the tent. By providing the lower edge of the tent canvas with suitable eyelets for engagement over the hooks, the wall thereof will be held tightly in place upon the frame, thus avoiding the necessity of using a plurality of guy ropes.

Having thus described my invention, what I claim is—

1. A tent frame structure comprising a plurality of poles designed to be arranged in substantially upright position, each of said poles having its upper end angled to provide an oblique face, a plurality of arms each having one end angled to provide an oblique face adapted to abut a complementarily formed face of a pole when the frame is set up to hold the arms in a fixed position, hinge elements connecting said arms with the adjacent poles, collapsible brace elements connecting each of the arms with the adjacent pole, a central block member having the other ends of said arms pivotally connected thereto, and a center stub pole threadably extended through said central member.

2. A tent frame structure comprising a plurality of poles designed to be arranged in substantially upright position each of said poles having its upper end angled to provide an oblique face, a plurality of arms each having one end angled to provide an oblique face adapted to abut a complementarily formed face of a pole when the frame is set up to hold the arms in a fixed position, hinge elements connecting said arms with the adjacent poles, collapsible brace elements connecting each of the arms with the adjacent pole, a central block member having the other ends of said arms arranged to abut against side faces thereof, hinge members upon the upper faces of said arms and said central member pivotally securing the arms thereto to permit their collapsing movement downwardly, and a threaded stub pole extending through said central member for vertical adjustment thereon.

In testimony whereof I hereunto affix my signature.

DAN STROMBECK.
